UNITED STATES PATENT OFFICE

LEWIS M. CLEMENT, OF MOUNTAIN LAKES, NEW JERSEY, ASSIGNOR TO WESTERN ELECTRIC COMPANY, INCORPORATED, OF NEW YORK, N. Y., A CORPORATION OF NEW YORK

SYSTEM OF SPACE DISCHARGE TUBES

Application filed June 30, 1924. Serial No. 723,147.

This invention relates to systems of space discharge tubes and more particularly to radio transmitting systems having means for maintaining suitable average potentials upon 5 certain electrodes of space discharge tubes included therein.

It has been customary heretofore to utilize the energy of current flowing in the space path of space discharge tubes for supplying 10 suitable polarizing potentials to tube control electrodes. One way in which this result has been accomplished has been to include a resistance in a path common to the output and input circuits of the space discharge tubes, in such manner that when current flows therein a voltage will be impressed 15 upon the tube control electrodes by virtue of the drop of potential along the resistance. An advantage of such arrangement is the 20 elimination of expensive and bulky apparatus such as batteries or condensers which are ordinarily used to secure the proper control electrode potentials. A serious disadvantage, however, which results from such arrangements, as heretofore used, is that when a negative 25 potential is applied to the tube control electrodes by the drop of potential in the resistance, a condition favorable to cyclic blocking and unblocking of the tubes is created.

30 It is an object of the invention to stabilize systems of space discharge tubes.

It is another object to provide means for maintaining suitable average potentials upon the control electrodes of space discharge 35 tubes.

A further object is to prevent blocking and unblocking of the tubes in space discharge tube systems in which the control electrodes of the tubes are polarized by means of the 40 drop in potential along a resistance.

A feature of the invention relates to means for maintaining a continuous flow of current through a resistance common to the input and output circuits of space discharge tubes for 45 increasing the stability of the system.

In general, the invention may include a resistance connected in common to the input and output circuits of space discharge tubes which may form a part, for example, of a 50 radio transmitting system. A source of space

current is connected in series with the resistance, and a shunt path about the resistance and the space current source is provided for maintaining a continuous flow of current through the resistance. This path may include another resistance adjusted to a suitable value for maintaining the proper flow of current.

In the drawing, a radio transmitting system is illustrated which embodies the invention.

The radio transmitting circuit shown in the drawing includes an antenna 10 electrostatically coupled to a space discharge tube power amplifier 20 supplied with oscillations 55 from a high frequency oscillator 30 and arranged to be controlled by a space discharge tube power modulator 40 supplied with low frequency waves from a low frequency oscillator 50. The system is arranged to be controlled by a source of signals represented by a telegraph key 51.

The antenna 10 is connected to ground in series with an adjustable loading coil 11, variable condenser 12, and high frequency ammeter 13. Condenser 12 is provided to couple the antenna circuit to tuned circuit 14 including a portion of the variable inductance 15 and the condenser 16. This tuned circuit is included in the high frequency output circuit of amplifier 20 which includes the space discharge tube 21. This output circuit may be traced as follows: from the plate of tube 21, choke coil 22, blocking condenser 23, resonant circuit 14, choke coil 24 to ground 80 through condensers 25 to the filament of tube 21. The purpose of the choke coil 24 is to provide a path of suitable impedance to high frequency waves from the antenna to ground when the switch 17 is thrown to its left hand contact to connect the antenna to a counterpoise 18 instead of to ground. The tube 21 has an input circuit connected to its control electrode and cathode which may be traced from the control electrode through resistance 26, choke coil 31, resistance 32, ammeter 36, to the intermediate tap of resistance 33 through the left hand portion of resistance 33 to ground and from ground through secondary winding of transformer 45, resistances 86, to 85

90

95

100

the filament of tube 21. Resistances 86 are provided to adjust the filament current and to balance the filament heating circuit. Condensers 25 are provided to supply a low impedance path for high frequency waves about the transformer winding and resistances 86, and also to balance the circuit.

The portion of the resistance 33 included in this input circuit is also included in a space current circuit of tube 21 connected to its anode and cathode. This circuit may be traced from the plate of tube 21, choke coil 22, choke coil 41, ammeter 42, low frequency choke coil 43, generator 44, resistance 33 to ground, and thence to the cathode of tube 21 via the path traced above. The generator 44 is shunted by a condenser 73 for reducing ripples in the space current by providing a low impedance path therefor. The input circuit of amplifier 20 is directly connected to the input circuit of space discharge tube 34 of oscillator 30. The input circuit of tube 34 may be traced from its control electrode through choke coil 31, resistance 32, ammeter 36, intermediate tap on resistance 33 to ground, thence to secondary winding of transformer 45, resistances 88 to the cathode of the tube. Condensers 64 and resistances 88 are provided at this tube for the same purpose as the corresponding elements at tube 21.

The portion of the resistance 33 included in the input circuit of tube 34 is also included in its space current circuit. The space current circuit of tube 34 may be traced from its anode through choke coil 35, inductance 38, ammeter 52, choke coil 53, resistance 54, generator 44, resistance 33 to ground and thence to the midpoint on the secondary winding of transformer 45, resistance 88, and the cathode of tube 34. The high frequency output circuit of tube 34 includes its anode, high frequency choke coil 35, resonant circuit 37 to ground, and thence through condensers 64 to the cathode of tube 34. The resonant circuit 37 includes a portion of the inductance 38 shunted by condensers 39 and 48. An ammeter 49 is connected between the condensers 39 and 48. Connection to ground is made between the ammeter 49 and the condenser 48. A blocking condenser 90 is provided to prevent direct current from the space path of tube 34 from flowing in the grid circuit of the tube.

The output circuit of tube 34 is coupled to its input circuit by the inductance 38, whereby energy is fed from the output circuit to the input circuit for the purpose of generating sustained oscillations. These oscillations are supplied from the input circuit of tube 34 to the input circuit of tube 21 of amplifier 20.

The output circuit of the amplifier tube 21 is coupled to the alternating current output circuit of modulator tube 55. The latter may be traced from the anode of tube 55 through

choke coil 56, ammeter 57, ammeter 42, bypass condenser 58 to ground, thence to condensers 25' and to the cathode of tube 55. The space current circuit of tube 55 may be traced from the anode of this tube through choke coil 56, ammeter 57, low frequency choke coil 43, generator 44, resistance 33, to ground at midpoint of secondary winding of transformer 45, resistances 87 to the cathode of the tube. The input circuit of tube 55 is connected to its control electrode and cathode and extends from the control electrode through resistance 59, shunted by the secondary winding of transformer 60, resistance 33, shunted by condenser 61 to ground, and thence to the mid-point of the secondary of transformer 45 and to the cathode of the tube.

The low frequency oscillator 50 comprises the three-electrode space discharge tube 62 having an input circuit connected between its control electrode and cathode which includes one winding of transformer 63, ground, secondary winding of transformer 45, and switch 100. The alternating current output circuit of this tube is connected to its anode and cathode, and includes condenser 65, resistance 66, resistance 67, ground, secondary winding of transformer 45, and switch 100. A feed-back circuit is connected to the anode and cathode and includes condenser 65, adjustable resistance 68, primary winding of transformer 63 shunted by condenser 69, ground, secondary winding of transformer 45, and switch 100. This feed-back circuit is arranged to supply energy to the input circuit by virtue of the coupling between the windings of transformer 63, whereby sustained oscillations are generated. The frequency of these oscillations is determined by the constants of the condenser 69 and the windings of transformer 63 in shunt thereto. The space current is supplied to tube 62 over a path connected to its anode and cathode which includes low frequency choke coil 70, resistance 71, generator 44, and resistance 33.

The output circuit of tube 62 is connected in energy transfer relation to the input circuit of tube 55 by a line connected to the terminals of resistance 67 which includes filter 74 or 75, switches 76 and 77 and the primary winding of transformer 60. Either one of filters 74 or 75 may be included in this circuit by actuating switches 76 and 77.

For controlling the operation of the system, a telegraph key 51, shunted by a series arrangement of resistance 78 and condenser 79, has its contact and lever connected to the grounded terminal and the midpoint of resistance 33, respectively. If desired, the key 51 may be replaced by the contacts of a relay arranged to be operated by a switch at a distant point. The space discharge tube system or radio transmitter could then be remotely controlled.

Current for heating all of the cathodes of

the various tubes is supplied from a common source represented as an alternating current generator 80 which is connected to the primary winding of the transformer 45. The 5 secondary winding of this transformer is tapped at various points by leads 46, 82, and 83 for supplying current to the cathodes of tubes 34, 62, and 55 and 21, respectively. The midpoint of the secondary winding of transformer 81 is connected to ground. This 10 system is arranged for operation by continuous waves or by modulated continuous waves.

A resistance 85 is connected in shunt to the generator 44 and resistance 33.

15 In the operation of this system as a modulated continuous wave system, high frequency oscillations generated by oscillator 30 are supplied to the input circuit of space discharge tube 21 of amplifier 20. These oscillations are preferably of a frequency above the audible range. Low frequency oscillations are likewise supplied from the output circuit of tube 62 through the filter 74 or 75, as the case may be, and transformer 60 to 20 the input circuit of tube 55 when switch 100 is closed. Oscillator 50 is preferably adjusted to generate the oscillations within the audible range of frequencies.

25 Filters 74 and 75 are designed to prevent 30 the transmission of waves of harmonic frequencies which may be generated by the oscillator 50. Filter 74, for example, may be a low pass filter designed to pass currents of frequencies below 600 cycles per second only, 35 whereas filter 75 may be designed to pass currents of frequencies below 1200 cycles per second.

By virtue of the connection between the 40 output circuits of tubes 55 and 21, the high frequency waves produced in the output circuit of tube 21 are modulated in accordance with the low frequency waves in the output circuit of tube 55. These modulated waves are transmitted through the coupling afforded by condensers 12 and 23 to the antenna 10 and are radiated therefrom. As a means of 45 signaling, the telegraph key 51 is arranged when operated to short circuit a portion of the resistance 33 sufficient to reduce the negative potential upon the control electrodes of tubes 21, 34, and 55, whereby they are placed in operative condition. Consequently, during the time that key 51 is closed, the high 50 frequency waves from oscillator 30 modulated in accordance with low frequency waves from oscillator 50 are transmitted from antenna 10. On the other hand, during the time that key 51 is open, resistance 33 impresses a negative potential upon the control electrodes of tubes 34, 21, and 55 sufficient to greatly reduce or stop the flow of space current therein and consequently sufficient to prevent the transmission of waves therefrom. Oscillator 50 remains in operative condition 55 at all times so long as switch 100 is closed.

In operating the system as a continuous wave system, the switch 100 is opened. The oscillator 50 is thereby rendered inoperative and only high frequency waves are transmitted from the antenna when key 51 is operated.

A resistance 85 is connected in shunt to the generator 44 and resistance 33 for the purpose of maintaining a continuous flow of current through resistance 33, as a means of preventing blocking and unblocking of the tubes of the system when key 51 is open. This tendency of the tubes to block and unblock is caused by the fact that an increase of space current causes an increase in the 80 drop of potential along the portion of resistance 33 included in the tube input circuits. This increased potential increases the negative polarization of the tube control electrodes which has the effect of reducing the 85 flow of space current. This in turn tends to reduce the potential applied to the control electrodes which results in an increased flow of space current. Resistance 85 is provided to maintain at all times the proper flow of 90 current through resistance 33.

Various ammeters are included in the circuit for indicating the flow of current therein. Ammeter 13 is provided to indicate the antenna current. Ammeter 13' is included 95 in the resonant circuit 14 to indicate the flow of current in this circuit. Likewise, ammeters 42, 57, 52, 36, and 49 are provided for indicating the flow of current in the particular circuits with which they are associated.

Choke coils 35, 22, and 56 are provided in the leads connected to the anodes of tubes 34, 21, and 55 for preventing the generation of parasitic oscillations or singing. Resistance 26 is included in the lead connecting the control electrodes of tubes 21 and 34 for, supplementary to choke coil 22, preventing the generation of parasitic oscillations or singing in the amplifier tube 21.

Condenser 73, connected in shunt to generator 44, is provided to supply a low impedance path for current variations such, for example, as commutator ripples. Likewise, condenser 61 connected in shunt to resistance 33 provides a low impedance path for variable components of current as a means for preventing these variations from being transmitted as variations of potential to the control electrodes of tubes 21, 34, and 115 55. Resistances 86, 87, and 88 and condensers 25, 25', and 64 are provided in the filament heating circuits of tubes 21, 55, and 34 for balancing these circuits to prevent the introduction of current variations corresponding 120 to the variations of source 80 into the circuits connected to the anodes and control electrodes of these tubes. The condenser 58 is provided to prevent the loss of power at the high frequencies in the choke coil 43. This 125 130

condenser provides a low impedance path to ground in shunt to the choke coil 43, generator 44, and resistance 33.

Adjustable resistance 59 enables low frequency waves of the proper voltage to be impressed upon the input circuit of tube 55.

Condenser 65 in the circuit of low frequency oscillator 50 is provided to prevent the passage of direct current from source 44 through the alternating current output circuit of the tube. Adjustable resistance 68 is provided to enable the energy fed back from the output circuit to the input circuit to be adjusted to the proper value for producing sustained oscillations.

The right hand portion of resistance 33 is provided to supply a suitable polarized potential to the control electrode of tube 55 during the time when key 51 is closed.

Resistance 67 is a coupling resistance designed to provide the proper potential for operating the modulator tube 55. Resistance 66 which is in series with resistance 67 cooperates with it in producing this result.

Although this invention has been illustrated and described in connection with a particular embodiment of the invention, it is intended to be limited only as indicated by the scope of the appended claims.

What is claimed is:

1. In a space discharge device system, a space discharge device comprising an anode, a cathode, and a control electrode, means for maintaining suitable average potential upon the control electrode of said device comprising a source of space current, a direct current path connected to the terminals of said source and including said anode and cathode in series with a resistance, a connection to said control electrode from a point in said resistance, and a second direct current path including a constant resistance external to the space discharge device in shunt to a portion of the first named direct current path.
2. In a space discharge system, a space discharge device having a plurality of electrodes including a control electrode, an anode, and an electron emitting cathode, means for maintaining suitable average potentials between the control electrode and cathode of said device which comprises a direct current source connected to said anode, a resistance in series with said source and cathode, a path between said control electrode and said cathode, which also includes said resistance, and a direct current path including a constant resistance external to the space discharge device connected across the terminals of the series path including said source and said first named resistance.
3. In a space discharge device system, including a plurality of space discharge devices each having an electron emitting cathode, an anode and an impedance controlling electrode, means for applying polarizing po-

tentials to said control electrodes comprising a resistance and a source of current included in a path between said anodes and said cathodes, a path which also includes said resistance connected between said cathodes and said control electrodes and a resistance external to said space discharge devices connected to said first mentioned resistance and to the terminal of said source remote therefrom for maintaining a continuous flow of current through said first mentioned resistance.

4. In a radio transmitting system including a space discharge device having a control electrode, cathode and anode, means for applying suitable negative potentials to the control electrode of said device, comprising a resistance connected between the control electrode and cathode and included in series with a source of current, signaling means connected to permit short-circuiting a portion of said resistance, and a direct current path in shunt to said resistance and said source.

5. In a radio transmitting system including a plurality of space discharge devices, means for applying to the control electrodes of certain of said devices a negative potential sufficient to block the flow of space current therethrough, means for preventing automatic unblocking of said devices, and signaling means arranged to control the flow of space current in said tubes.

6. In a radio transmitting system, a plurality of space discharge tubes each including a cathode, anode and control electrode, a resistance traversed by space current in said tubes, said resistance being connected to the control electrodes thereof, signaling means arranged to short circuit a portion of said resistance, and means for maintaining a continuous flow of current through said resistance.

7. In combination, a space discharge tube having a cathode and an anode and a control electrode, an input circuit connected to the control electrode and cathode and an output circuit connected to the anode and cathode of said tube, a resistance included in both of said circuits, and a source of current included in said output circuit in series with said resistance, signaling means arranged to short-circuit a portion of said resistance and a direct current path connected to said anode and cathode in parallel with said source and said resistance.

8. In a radio transmitting system, an antenna, a space discharge tube amplifier having input and output circuits, coupled to said antenna, a space discharge tube modulator coupled to the output circuit of said amplifier, a high frequency oscillator coupled to said input circuit, a low frequency oscillator and a source of signals, and means for rendering said system operative to transmit, in

accordance with said signals, high frequency waves modulated by low frequency oscillations, said means including a resistance traversed by space current from said tubes and means to maintain a continuous flow of current through said resistance.

common source and applied simultaneously to the grids of said triodes.

15. In a radio transmitting system, a source of radio frequency oscillations comprising a triode, an amplifier comprising a triode, an audio frequency source comprising a triode, connections whereby said amplifier may be jointly controlled by said radio frequency and said audio frequency sources, a common source of plate potential for said triodes, means for deriving a negative potential from said common source, and a keying device for controlling the application of said negative potential to the grids of said triodes. 70 75

16. In a radio transmitting system, a source of radio frequency oscillations comprising a triode, an amplifier comprising a triode, a source of audio frequency oscillations comprising a triode, connections whereby said amplifier may be jointly controlled by said sources of radio and audio frequency oscillations, a common source of high potential for the plates of said triodes, resistance connected in shunt to said source, connections whereby said resistance serves to negatively bias the grids of said triodes with respect to their cathodes, and means for establishing a shunt around at least a portion of the resistance which supplies said negative bias.

17. In a radio transmitting system, a source of carrier oscillations comprising a triode, an amplifier comprising a triode, an audio frequency source comprising a triode, a common source of plate potential for said triodes, means for deriving a negative potential from said common source, and additional means for applying said negative potential at will to the grids of said triodes. 95
100

18. In a high frequency signaling system employing a master oscillator and power amplifier for oscillations produced by said oscillator, said oscillator and said amplifier being of the vacuum tube type, a source of potential for the anodes of said oscillator and said amplifier, a permanent connection between the grids of said oscillator and said amplifier and the negative side of said source of potential, a connection between the cathodes of said oscillator and said amplifier and the negative side of said source of potential, means for controlling the operation of said oscillator and said amplifier comprising a contact making key inserted in said last mentioned connection, one side of said key being

connected to the negative side of said source of potential and to said grids, and the other side of said key being connected to the cathode, and means associated therewith and adapted to maintain a definite potential on said grids and across said key when said key is open. 120 125

In witness whereof, I hereunto subscribe my name this 25th day of June, A. D. 1924.

LEWIS M. CLEMENT. 130
